US00D865841S

(12) **United States Design Patent** (10) **Patent No.:** **US D865,841 S**
(45) **Date of Patent:** **** Nov. 5, 2019**

(54) **SURVEILLANCE CAMERA**

(71) Applicant: **BITRON VIDEO S.R.L.**, Turin (IT)

(72) Inventor: **Francesca Dattila**, Caluso (IT)

(73) Assignee: **SmaBiT GmbH**, Berlin (DE)

(**) Term: **15 Years**

(21) Appl. No.: **29/637,833**

(22) Filed: **Feb. 22, 2018**

(30) **Foreign Application Priority Data**

Sep. 6, 2017 (EM) 004244549

(51) **LOC (12) Cl.** **16-01**

(52) **U.S. Cl.**

(57) **CLAIM**

The ornamental design for a surveillance camera, as shown.

DESCRIPTION

FIG. 1 is a perspective view of a surveillance camera showing my new design;

FIG. 2 is a front view;

FIG. 3 is a rear view;

FIG. 4 is a left side view;

FIG. 5 is a right side view;

FIG. 6 is a top view; and,

FIG. 7 is a bottom view.

1 Claim, 7 Drawing Sheets

US D865,841 S
